UNITED STATES PATENT OFFICE.

ROBERT W. WIEDERWAX, OF ATLANTIC CITY, NEW JERSEY, ASSIGNOR OF ONE-HALF
TO CARLTON GEIST, OF ATLANTIC CITY, NEW JERSEY.

PREHEATER.

1,402,331.

Specification of Letters Patent.

Patented Jan. 3, 1922.

Application filed April 6, 1920. Serial No. 371,689.

To all whom it may concern:

Be it known that I, ROBERT W. WIEDERWAX, a citizen of the United States, residing at Atlantic City, in the county of Atlantic 5 and State of New Jersey, have invented certain new and useful Improvements in Pre-heaters, of which the following is a specification.

This invention relates to preheaters, and 10 more particularly to preheaters particularly adapted for use in heating castings preparatory to welding the same.

As is well known, in welding castings by means of the oxyacetylene torch, it is necessary to preheat the castings to prevent warping and cracking of the same during the welding operation. Heretofore, this has been accomplished by means of building up furnaces within which the casting was 20 placed and surrounded by charcoal or the like, which is ignited and allowed to burn until the casting has been heated.

I have devised an apparatus whereby ordinary illuminating gas or the like may be utilized for preheating castings. This device consists broadly of a casing having arranged therein a mass of small pieces of refractory aggregates. Arranged below the casing and provided with outlets extending 30 upwardly into the casing and into the refractory aggregates therein are banks of gas burner tubes, through which the combustible fuel is admitted. The combustible fuel passes upwardly through the aggregates and 35 when ignited, burns therebetween causing the aggregates to become rapidly incandescent.

In the accompanying drawings forming a part of this specification and in which like 40 numerals are employed to designate like parts throughout the same,

Figure 1 is a longitudinal section taken through an apparatus embodying my invention,

45 Figure 2 is a section taken on line 2—2 of Figure 1,

Figure 3 is a section taken on line 3—3 of Figure 1, support bars being omitted for the purpose of clarity,

50 Figure 4 is a fragmentary perspective

showing the manner of supporting the support bars, and,

Figure 5 is a sectional view showing a slightly modified form of my invention, wherein the support bars are formed integral with the gas burner tubes of the banks. 55

In the drawings, wherein for the purpose of illustration is shown a preferred embodiment of my invention, the numeral 10 designates a casing substantially rectangular in 60 outline and formed of substantially U-shaped side members having the arms of the U directed toward the interior of the casing.

Secured to each side of the casing 10 by means of bolts 12 are plates 13 providing 65 apertures through which extend gas burner tubes 14, connected in banks, one bank being disposed upon each side of the casing. It will be seen by inspecting Figure 2 that the gas burner tubes are arranged immediately 70 below the lower ends of the side walls of the casing. Each bank of gas burner tubes is connected with a feeding conduit 15, and each burner tube is provided with a governing valve 16, by means of which the admission of the gaseous fuel to the tube is governed. A common feed pipe 17 is provided, which is detachably connected, as at 18, to the conduits 15. It will be seen that, as the 75 plates 13 are detachably connected to the casing and the conduits 15 are detachably connected with the feeder conduit 17, that either of the banks of gas burner tubes may be readily removed for repairing or the like. 80

It will be noted that the upper surfaces of 85 the gas burner tubes are disposed beneath the bottom flange 19 of the casing and that these tubes have projecting upwardly therefrom outlets 20 which extend into the casing and are provided upon their upper ends with 90 removable caps 21, for a purpose presently to appear. Supports 22 are provided, which extend beneath the gas burner tubes 14 adjacent the outer ends thereof. These supports have their upper end bent upwardly, as at 95 23, and again outwardly, as at 24, the portion 24 resting upon the lower flange 19 of the casing wall. By inspecting Figures 1 and 2, it will be seen that the supports 22 extend longitudinally of the banks of gas burner 100

tubes and transversely of the tubes themselves. It will be further seen, by inspecting Figure 2, that each bank of tubes is composed of alternating long and short tubes 5 and that the supports 22 pass beneath the short tubes adjacent the outer ends thereof.

The short tubes of each bank are disposed opposite the long tubes of the other bank, and these tubes therefore, combine to form 10 practically an unbroken surface across the open bottom of the casing. The gas outlets 20 of the long tubes are staggered with relation to those of the short tubes and the fuel is thus very thoroughly disseminated 15 throughout the area of the casing. This dissemination is completed by the refractory aggregates 26 which are arranged within the casing and which cause the fuel to flow through tortuous passages formed by the 20 particles of the aggregate within the casing.

It will be obvious that in order to support the aggregates so as to allow the admission of air for combustion and at the same time prevent the aggregates from passing between 25 the gas burner tubes 14, some further support other than the tubes themselves is necessary. For this purpose, the construction shown in Figures 4 and 5 has been adopted. In Figure 4, the auxiliary supports are shown in 30 the form of angle irons 27, having their ends disposed upon and supported by the bottom flange 19 of the casing, the angle irons being arranged parallel to and intermediate each pair of gas burner tubes. These angle irons 35 should be of such size that their upper surfaces are disposed below the upper ends of the gas outlet tubes 20. In the form shown in Figure 5, the supports 27 are formed integrally with the gas burner tubes 14. This is 40 accomplished by providing the gas burner tubes with co-acting flanges which extend into proximity to one another but provide spaces, as at 28, through which air for combustion may be admitted. It will be obvious 45 that the flanges need not be formed upon the base of the gas burner tubes, as shown, but might conveniently be formed elsewhere and that the illustration shown is not intended to be in any manner limiting.

50 The upper face of the casing of the pre-heater is provided with a plurality of spaced transverse bars 28'. These bars are secured to the casing in any suitable manner.

It is to be understood that the forms of my 55 invention herewith shown and described are to be taken as a preferred example of the same, and that various changes in the shape, size, and arrangement of parts may be resorted to without departing from the spirit of my invention or the scope of the subjoined claims.

Having thus described my invention, I claim:

65 1. In apparatus of the type described, a casing having an open top and bottom, a plurality of gas burner tubes arranged adja-

cent the open bottom of said casing and co-acting to form a grid, refractory aggregates within said casing and supported by said grid, an inwardly extending flange formed on said casing, and a member arranged transversely of said gas burner tubes and contacting the lower face thereof to support the tubes, said member having portions resting upon the flange of said casing. 70

2. In apparatus of the type described, a 75 casing having an open top and bottom and provided with an internal flange, a plurality of spaced gas burner tubes arranged adjacent the open bottom of said casing and provided with upwardly extending outlets and 80 supports having their ends resting upon said flange arranged intermediate the outlet tubes of said gas burner tubes, and refractory aggregates within said casing and resting upon said gas burner tubes and said supports. 85

3. In apparatus of the type described, a casing having an open top and bottom and provided with an internal flange, a plurality of spaced gas burner tubes arranged adjacent the open bottom of said casing and 90 provided with upwardly extending outlets, and supports having their ends resting upon said flange arranged intermediate the outlet tubes of each of said gas burner tubes and the outlet tubes of the next adjacent gas 95 burner tubes.

4. In apparatus of the type described, a casing having an open top and bottom and provided with an internal flange, a plurality of gas burner tubes arranged beneath said 100 casing and provided with upwardly extending outlet tubes, supports arranged intermediate said outlet tubes and having their ends resting upon said flange, said supports being free from connection with said casing 105 and being held against transverse displacement by said outlet tubes, and refractory aggregates within said casing resting upon said supports.

5. In apparatus of the type described, a 110 casing having an open top and bottom and provided with an internal flange, a plurality of gas burner tubes arranged beneath said casing and provided with upwardly extending outlet tubes, supports arranged intermediate said outlet tubes and having their 115 ends resting upon said flange, said supports being free from connection with said casing and being held against transverse displacement by said outlet tubes, and refractory aggregates within said casing resting upon said supports, said outlet tubes terminating above said supports.

6. In apparatus of the type described, a 125 casing having an open top and bottom, a plurality of gas burner tubes arranged adjacent the open bottom of said casing and coacting to form a grid, a plurality of transverse supporting members arranged beneath said burner tubes and acting as a support 130

therefor, said supporting members being secured to the walls of the casing and being positioned below the open bottom of the casing, and refractory aggregates within said 5 casing and supported by said grid.

7. In apparatus of the type described, a casing having an open top and bottom, a plurality of supporting members arranged beneath the bottom of the casing, the ends 10 of said supporting members being extended upwardly and secured to the walls of the cas-

ing, a plurality of gas burner tubes arranged on said supporting members and co-acting to form a grid, and refractory aggregates within said casing and supported by said grid. 15

In testimony whereof I affix my signature in presence of two witnesses.

ROBERT W. WIEDERWAX.
